UNITED STATES PATENT OFFICE.

LEON E. LA BOMBARD, OF LAWRENCE, MASSACHUSETTS.

FEEDER FOR BLANKS OR SHEETS.

1,285,007.

Specification of Letters Patent. Patented Nov. 19, 1918.

Application filed January 3, 1916. Serial No. 69,942.

To all whom it may concern:

Be it known that I, LEON E. LA BOMBARD, of Lawrence, in the county of Essex and State of Massachusetts, have invented certain new and useful Improvements in Feeders for Blanks or Sheets, of which the following is a specification.

This invention relates to the manufacture of boxes, and particularly to the production of paper boxes which, since they are made of a plurality of members, may be termed "compound boxes."

There are certain kinds of paper boxes each of which comprises a body portion so shaped as to contain articles, such as candy, and a band member or retaining member which surrounds and incloses the portion of the body member which holds the goods, said band member serving to lock the body member in receptacle condition. Boxes of this type would be very expensive to make, if each box were formed from a single blank, because there would be a great waste of material in cutting out the blanks. Hence, it is customary to make such boxes of two blanks or members which are adhesively connected. So far as I am aware, the assembling of the blanks in pairs, so as to fit them to be afterward set up into receptacle form to hold goods, has only been done by hand. The principal object of this invention is to provide a feed mechanism for a machine which will accurately, rapidly and economically assemble and unite a plurality of blanks (in the present case, two), the machine turning out the product in flat condition, in which collapsed condition the boxes may be conveniently shipped and stored, and afterward opened out or set up. With the above and other objects in view, my invention consists in the improvements which I shall now proceed to describe and claim.

Of the accompanying drawings:

Figure 1 represents a longitudinal sectional view of a portion of a machine having my improved feed mechanism.

Fig. 2 is a side elevation, partly in section, of one of the feed controlling mechanisms, said view being on a larger scale than Fig. 1.

Fig. 3 is an elevation looking from the left of Fig. 2.

Fig. 4 is a detail view of an upper portion of the blank arresting or stop slide. 55

Fig. 5 represents a section on line 5—5 of Fig. 3.

Fig. 6 represents a section on line 6—6 of Fig. 5.

In a preliminary way, and to facilitate an understanding of the machine and its operation, I will state that the machine has two hoppers, one of which is supplied with piles of the body blanks and the other with a pile of the strip or band blanks. 60 65

At one end of the frame 25 there are two hoppers from which the two kinds of blanks *a* and *d* are fed singly and in timed relationship, as hereinafter described. The blanks *a* pass from hopper 26 between belts 27, 28 the lower one being mounted on pulleys 29, 30, (Fig. 1) and the upper belt being mounted on pulleys 31, 32. Suitably mounted belt-tightening rolls are indicated as 33. Near the pulleys, 29, 31, are rolls 34, 75 the upper ones being mounted in spring carriers. These rolls as well as the pulleys 29, 31, act to hold the co-operating stretches of the belts 28, 27, in such close proximity as to insure the blanks being carried along 80 without slipping. Further along in the machine, the said belts are less close together. A platform 35 supports the intermediate portion of belt 27.

Before describing further action of the machine upon the body blanks *a*, I will refer to the blanks *d* which are longer and narrower than the blanks *a*. The hopper 36, like the hopper 26, has means for feeding the blanks singly. Said means will be described in detail hereinafter. Each blank *d* leaving the hopper 36, passes between two inclined guide plates 37, 38 underneath which is a glue pot 39 containing a rotating glue roll 40. Said glue roll is so mounted 90 that the upper portion of its periphery is sufficiently below the plane of normal movement of the blanks *d* to prevent contact of a passing blank with the glue carried by said periphery. Localized contact, however, is effected by two blank-depressing fingers 41, the plates 37, 38 having openings to permit this to be done. The fingers are carried by a continuously rotating shaft 42, the angular tips of said fingers being so 105 spaced apart that they act, respectively,

upon the rear end of one blank *d* and the adjacent or front end of the next blank *d*. In other words, the blanks *d* are fed successively from hopper 36, and are taken by 5 the lug-carrying chain presently described, with spaces between the blanks slightly less than the space between the fingers 41 so that said fingers depress the adjacent ends of two blanks almost, but not quite, simultaneously 10 to cause small areas of glue to be applied thereto.

A chain 43, carrying properly spaced lugs 44, is mounted on pulleys carried by shafts 45, 46 said chain passing under a sprocket 15 47 to cause the chain to travel horizontally for a portion of its movement. To cause each blank issuing from hopper 36 to be positively advanced between the plates 37, 38 far enough to enable its rear end to be engaged 20 by a lug of the chain, the shaft 45 has a feed disk 48 formed or provided with a friction periphery. This disk and a co-operating supporting roll 49 act through suitable openings in the plates 37, 38 to grasp 25 a blank *d* and advance it as described.

Returning now to the blank *a*, it is to be understood that it approaches the point of convergence with a blank *d*, slightly ahead of said blank *d*. This is because a lip portion 30 thereof is to be turned up and backward as presently described. The blank *a* is carried along far enough to reach the zone of action of two chains 51 side by side and having properly spaced lugs 52, one of said 35 chains being shown in Fig. 1. Said chains are mounted on sprockets carried by shafts 53, 54. When the rear edge of the blank *a* is engaged by the chain lugs, it is thereafter pushed along by said lugs. When the front 40 end of the blank reaches the hook folder 56 which is pivotally mounted at 57 and normally held against a stop 58 by a spring 59, said hook first yields and then pulls the front end up and over backwardly. Of course the 45 blank is moving along during this time. The band blank *d* is also moving toward the junction point and when the front end of blank *a* leaves the tip of the hook folder, said end snaps up against the under side of 50 the front end portion of blank *d* having the glue. The front portions of the two blanks, thus assembled, pass between upper and lower compression belts 60, 61.

The upper belt is mounted on pulleys one 55 of which is carried by shaft 62, and the lower belt is mounted on pulleys one of which is carried by shaft 64.

Just after the assembled front portions of 60 the two blanks are taken by the compression belts, their rear portions reach positions for the portion of blank *d* (which is still extending considerably to the rear of blank *a*) to be folded. The device which does this folding 65 consists of an angular arm 71 secured to a rock shaft 72 having suitable means for actuat-

ing it at proper times to effect oscillation of of the folder arm 71. The timing is such that just as the rear end of blank *d* is approaching position under the arm 71, said arm swings and bends the rear portion of 70 blank *d* down and then up under the rear portion of blank *a*. It then quickly swings back to normal position. To render it certain that when arm 71 swings down it will bend or fold down only a definite rear part 75 of blank *d*, on a creased line, a flat finger 87 is secured to the upper end of a vertical shaft 88 mounted in a bracket 89. The lower end of shaft 88 has an arm 90 which is actuated by suitable mechanism to effect the 80 swinging of the finger 87.

I will now describe the improved feed mechanisms to insure delivery of the blanks from the two hoppers not only properly timed relatively to each other, but also relatively to the lugs of the feed chains already described, so that the two blanks of each pair will be carried along and acted upon and combined accurately. In most respects, the two feed devices are alike. I will first 90 refer to the feed mechanism for the body blanks *a*. Secured to a tie rod 103 are two rearwardly extending bars 104 which support the side members or walls 26 of the hopper. Fig. 1, being sectional, shows but 95 one of said bars. On the bars 104 are adjustably mounted a pair of brackets 105 which support a cross bar 106, the latter supporting an inclined narrow plate 107 against which the rear edges of the pile or stock of 100 blanks *a* bear. To suit sizes, shapes, and qualities of blanks, the brackets may be set forward or back on the bars 104, as by set screws 108, and the plate 107 may be secured in any desired position along the cross bar 105 106 or at any preferred angle of inclination, as by a set screw 109. The blanks are unsupported intermediate their front and rear edges, and therefore the inclination of the plate 107, when properly adjusted to hold 110 the blanks inclined upwardly toward the rear, causes the blanks to have a constant tendency to move forwardly to the front fixed but vertically adjustable inclined gage 110 having a beveled lower end (Fig. 2). 115

Secured upon rod 103, as by a set screw 111, is a sleeve 112 having an inclined bar bracket 113 to the rear face of which the bar 110 is secured by screws 114 passing through slots 115 in the bracket. An adjusting screw 116 passes through an ear at the top of the bracket 113 into the upper end of the bar 110 so that, when binding screws 114 are loosened, the gage bar 110 may be accurately adjusted to let the 120 bottom-most blank *a* pass between its lower end and the feed wheel 128 presently described.

The gage bar 110 is recessed or cut away (Figs. 5 and 6) to provide a space for the 125 130

slide 117 having a lateral ear 118 (Figs. 2 and 4) to which a spring 119 is connected so that the lower end of said slide will normally project below the gage bar 110 to serve 5 as a stop to prevent the bottom-most blank from passing. To lift this stop slide periodically, to permit a blank to pass, I provide an arm 120 projecting under the ear 118 from a rock shaft 121 mounted in the sleeve 112 10 and in a collar 122 also secured on rod 103, said rock shaft having a long arm 123 (Figs. 2 and 3) having a roll 124 that is kept in peripheral contact with a cam 125 on shaft 126, by a spring 127. The feed wheel 128 is 15 also carried by the shaft 126. Preferably, although not necessarily, the feed wheel is provided with one or more friction plugs 129.

The lower portion of the bracket 113 has a vertical front face to which is fitted a small 20 sliding bracket 130 having a vertical slot 131 through which a screw 132 passes into said bracket 113. Said bracket 130 carries a short shaft 133 on which are mounted two rolls 134 which are kept in rolling contact with 25 the feed wheel 128 by a spring 135 bearing on the top of the bracket 130.

The structure and timing of operation are such that the lower-most blank *a*, resting on the feed wheel 128 and the inclined plate 107 30 and consequently being constantly urged forward, can not pass so long as the stop 117 remains down as shown in Fig. 2. The moment that cam 125 actuates arm 123 however, the arm 120 lifts the slide stop and the said blank *a* is instantly started forward and keeps moving and is delivered to the belts 27, 28. Preferably the cam 125 is so shaped as to permit the slide stop to be acted upon by the spring 119 before the moving blank 35 40 has entirely passed, so that said stop will bear yieldingly on the rear-most part of that blank (the fore-most part having, by then, reached the nip of belts 27, 28), the stop descending in time to prevent another blank 45 from being fed until the stop is again lifted by the cam.

The feed wheel for the upper blanks *d* is indicated at 128^a in Fig. 1. For the most part, the mechanism of the upper feed is a 50 duplicate of that just described for the lower feed, and hence, in Fig. 1, I employ the same reference characters with the addition of the exponent *a*. There is one material difference, however, viz: for the upper 55 long narrow blanks *d* I prefer to supply a more sensitive kind of forward impeller for the blanks. Instead of the inclined plate 107 forming the rear of the lower hopper, in the upper hopper I employ a wheel 136 loosely 60 mounted on the rod or bar 106^a, this wheel being so supported that it may be adjusted to cause several of the lower blanks *d* to rest with their rear edges against the periphery of the wheel in front of its highest portion, 65 thus causing the tendency of the wheel to be

rotated by the weight and friction of the blanks, to aid in pressing those blanks forward. Excepting for the difference between the plate 107 and the wheel 136, the two feed mechanisms are substantially the same. 70 Owing to the fact that each feed mechanism has a movable stop which absolutely prevents the passage of a blank until the stop is shifted to open a passageway for such blank, and as the shifting of the stop can only occur at 75 timed intervals, the blanks necessarily issue from each hopper accurately spaced. The timing of the delivery of the blanks is so reliable that I may dispense with the belts 27, 28, and arrange the hopper and the lug-carrying chains in such proximity that the blanks will be delivered directly from the hopper to the chains and edge guides. 80

Owing to the fact that the blanks are supported only at the front and rear, as by the 85 wheel 128 and the plate 107 or the small wheel 136, there being no table or intermediate support for the pile, frictional resistance to the feed of each blank is reduced to the minimum. This is because, the moment 90 the bottom blank is started forward, its rear drops a little, or is at least free from the weight of the other blanks above it, and therefore there is nothing tending to hold it back or retard its outward passage. If a 95 blank *a* or *d* from either hopper should hesitate or be partly retarded, it might not reach position to be taken and pushed by a chain lug in time to be properly assembled with and united to its companion blank *a* or *d*. 100

Any suitable means are provided for preventing contact of any portion of a blank *d* with the glue wheel 40, except when depressed by a finger 41. In Fig. 1, I illustrate a light spring 162 rising from the top of 105 the glue pot 40 to a height which is somewhat exaggerated in said figure for the sake of clearness. In operation, this spring yields sufficiently to permit the selected portion of a blank to be depressed by a finger 110 41 into contact with the roll 40.

I do not claim herein mechanism for connecting the blanks *a* and *d* together, as the same forms the subject matter of my application filed Feb. 24, 1917, Serial No. 150679. 115 Said mechanism is described briefly herein to explain the reasons for accurately timing the feeds from the two hoppers in proper relationship.

Having now described my invention in 120 one of its embodiments, although without attempting to illustrate or describe all of the modifications or variations thereof, what I claim is:

1. A box-making machine having a pair 125 of containers for piles of blanks, continuously traveling feeders for advancing blanks singly from each pile, a movable barrier for each pile to positively prevent any blank from being advanced until the barrier is re- 130

moved, and means for moving both barriers to a limited degree at pre-determined times to permit two single blanks to be advanced one from each of the two containers, in 5 timed relationship.

2. A box-making machine having a pair of hoppers for blanks, each hopper having means for feeding out the lower blank of a pile therein, a movable stop for preventing 10 the escape of such blank, and means for periodically shifting said stop to permit the passage of the blanks one at a time and accurately spaced.

3. A blank feeding mechanism having 15 front and rear supports for a pile of blanks, the rear support being in position to contact with the rear edges of the blanks and urge them forward, the intermediate portions being unsupported, the front support 20 being movable to feed the lower blank of the pile, a stop movable to and from position to arrest the bottom blank of the pile, and means for periodically shifting said stop to permit the passage of the blanks one at a 25 time and accurately spaced.

4. A blank feeding mechanism having front and rear supports for a pile of blanks, the intermediate portions being unsupported, the front support being movable to 30 feed the lower blank of the pile, the rear support being mounted to maintain the blanks in forwardly inclined position and contacting with their rear edges to urge them forward, a stop movable to and from 35 position to arrest the bottom blank of the pile, and means for periodically shifting said stop to permit the passage of the blanks one at a time and accurately spaced.

5. A blank feeding mechanism comprising 40 a constantly rotatable feeding wheel in position to support the front of the blanks, a support for the rear edges of the blanks said support presenting an inclined surface for the said rear edges, a stop movable to and from position to arrest the bottom blank of the pile, and means for periodically shifting said stop to permit the passage of the blanks one at a time and accurately spaced.

6. A feeding mechanism for blanks, comprising means for supporting a pile of blanks, said means including a constantly 45 rotatable friction feeding wheel, a stop movable toward and from said wheel to close or 50 open a passageway for a blank, and means for periodically shifting said stop to alternately

permit and positively arrest the passage of blanks.

7. A feeding mechanism for blanks comprising upper and lower wheels for the passage of blanks between them, the lower wheel being constantly rotatable, a movable stop for preventing any blank from reaching the nip of said rolls except when the stop is shifted from arresting position, and means 60 for supporting a pile of blanks with the lowermost one having its forward portion resting on the said lower wheel.

8. A feeding mechanism for blanks comprising upper and lower wheels for the passage of blanks between them, the lower wheel being constantly rotatable, an inclined member having its lower end in proximity to but spaced from said lower wheel, a slide having its lower end normally crossing the 70 space between said inclined member and lower wheel, means for periodically raising said slide, and means for supporting a pile of blanks with their front edges against the lower end of the slide and the lower portion 75 of said inclined member.

9. A feed mechanism of the character described comprising a hopper for a pile of blanks, a rotary friction feeder, a stop movable toward and from the feeder, and means 80 for moving said stop at predetermined intervals to provide an alternately open and closed space between the stop and feeder.

10. A feed mechanism of the character described, comprising a hopper for a pile of 90 blanks, said hopper having an outlet or passageway for single blanks, means for intermittently opening and closing said outlet or passageway, and means for ejecting a blank through the outlet or passageway 95 when open.

11. A feed mechanism of the character described, comprising a hopper for a pile of blanks, said hopper having an outlet for single blanks, a movable stop adapted to 100 close said outlet, means for yieldingly shifting the stop in a direction to close the outlet, means for feeding a blank through said outlet when open, and means for actuating the stop to open the outlet to permit a blank to 105 start through and to release the stop to permit it to bear on the surface of the outgoing blank before it has entirely passed.

In testimony whereof I have affixed my signature.

LEON E. LA BOMBARD.
